UNITED STATES PATENT OFFICE.

OSCAR H. PIERCE, OF TORONTO, ONTARIO, CANADA.

TICKET-MARKING HOLDER.

Application filed October 4, 1928. Serial No. 310,399.

The principal objects of the invention are to facilitate the handling and marking of mercantile sale price and identification tickets and to provide a very simple and inexpensive device which will enable the handling of the tickets in groups or strips in such a manner as to lessen the liability of scratching or pricking the fingers with the sharp fastening prongs.

10 The principal features of the invention consist in providing a holder to support the tickets in a convenient position for marking having a guiding groove to receive the ticket pins and a clamping member to hold the tickets from shifting.

15

In the drawings, Figure 1 is a perspective view of my device showing a strip of sale price or identification tickets of the pin type in position thereon and the hinged clamping member turned back to allow the placing or removal of the strip.

Figure 2 is a view similar to Figure 1 showing a strip of tickets secured in position thereon ready for marking.

20 Figure 3 is a cross sectional view of Figure 2 showing the pins for securing the tag to the merchandise, housed within the guiding groove and the clamping member in position.

25 Many forms of sale price and identification tickets are used in the marking of clothing and textile merchandise and one very commonly used is provided with a sharp pointed U-shaped wire inserted through it close to its upper edge, the ends of which project beyond its rear surface. These tickets are usually printed and cut into individual tickets and sold in boxes, and as the ends of the wire fastening member are very 35 sharply pointed it requires a great amount of care on the part of the person allotted the duty of marking, to keep from pricking or scratching the fingers.

30 In cases where there is considerable ticket marking it is the usual practice to first secure the ticket to the goods and then mark the price or size thereon. This method of handling is very slow and owing to the fact that the tags are small and are frequently 40 very hard to separate it will be readily understood that it is not only a dangerous but a costly practice.

45 The present invention eliminates these objectionable features mentioned and in the 50 form shown a rectangular plate 1 of sheet metal is formed with a longitudinal rib 2

forming a vertical groove 3 extending parallel with and adjacent to one edge. This groove is deeper than the length of the pins 4 which fit into same and hold the tickets for 50 marking.

The extension 5 of the plate 1 adjacent to the rib 2 is preferably curved downward and is provided with hinge lugs 6 formed with a rolled outer edge 7 in which a hinge pin 8 is secured. A curved plate 9 provided with hinge lugs 10 rolled at the edge is pivotally mounted on the pin 8, the lugs 10 fitting between the lugs 6. A space 11 is provided centrally of the length of the plate 9 and the 60 plate 1 and a tension spring 12 supported on the pin 8 holds the edge 13 of the plate 9 normally against the plate 1 slightly forward of the groove 3. The other longitudinal edge of the plate 1 is preferably 65 formed with a bead 12' and the plate rests on the bead 12' and the rib 2 which supports the plate at a convenient slope for writing.

70 The marking tickets 14 are preferably 75 provided with transverse perforations and in using this invention a strip of tickets is placed thereon with the pin fasteners 15 inserted into the groove 3 and the free edge of the hinged holding member 9 is held by the spring 12 in contact with the strip of tickets as shown in Figures 2 and 3 and when thus held on the plate or holder they may be easily and conveniently marked. When the marking has been completed the holding member is raised by pressing backwardly on the lug 16 arranged at the end thereof and the ticket strip is removed. The tickets are then separated the one from the other and placed on the goods to be marked. This 80 means of handling the tickets obviously 85 lessens the risk of piercing or scratching the hands of the operator.

90 In handling other forms of tickets such as those without pins or with cord fastening means, the upper edge of the strip is inserted under and held by the holding member which protects the edge of the strip and supports same in proper position for 95 marking.

100 What I claim as my invention is:—

1. A ticket-marking holder comprising a member having a flat ticket-supporting surface and a guiding groove therein and means adapted to grip and hold the ticket in place on said surface.

110 2. A ticket-marking holder comprising a member having a flat ticket-supporting sur-

face and a guiding groove therein and spring means adapted to grip and hold the ticket on said surface.

3. A ticket-marking holder comprising a member having a flat ticket-supporting surface and a groove formed therein extending downwardly from the surface, a flange arranged adjacent to said groove, and a spring held member hinged to said flange and adapted to grip and hold the ticket in place on said surface.

4. A holder for marking tickets having pin fastening points projecting therefrom, comprising a member having a longitudinal

15 groove depressed in its top side adapted to

house the pin-fastening points, a flange along the edge of said member adjacent to said groove, a plate hinged to said flange, and a spring holding said hinged plate in contact with said grooved member.

5. A ticket-marking holder comprising a sheet-metal plate having a longitudinal rib formed therein forming a deep open groove in the top side, a curved flange extending beyond said groove, a curved plate hinged to 25 said flange, and a coiled tension spring normally holding the free edge of said hinged plate to the supporting surface of the ticket holder.

OSCAR H. PIERCE.
